(57) **CLAIM**

The ornamental design for a medical probes, as shown and described.

DESCRIPTION

The file of this patent contains at least one photograph executed in color. Copies of this patent with color photographs will be provided by the office upon request and payment of the necessary fee.

FIG. 1 is a front perspective view of a first embodiment of our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof;

FIG. 8 is a front perspective view of a second embodiment of our new design;

FIG. 9 is a front elevational view thereof;

FIG. 10 is a rear elevational view thereof;

FIG. 11 is a top plan view thereof;

FIG. 12 is a bottom plan view thereof;

FIG. 13 is a left side elevational view thereof; and

FIG. 14 is a right side elevational view thereof.

FIG. 15 is a front perspective view of a third embodiment of our new design;

FIG. 16 is a front elevational view thereof;

FIG. 17 is a rear elevational view thereof;

FIG. 18 is a top plan view thereof;

(Continued)

FIG. 19 is a bottom plan view thereof;
FIG. 20 is a left side elevational view thereof; and,
FIG. 21 is a right side elevational view thereof.
